UNITED STATES PATENT OFFICE.

HERBERT E. MARKS, OF GLEN OSBORNE, SEWICKLEY, PENNSYLVANIA.

ROOF CONSTRUCTION.

Application filed April 20, 1925. Serial No. 24,327.

To all whom it may concern:

Be it known that I, HERBERT E. MARKS, a citizen of the United States, and a resident of Glen Osborne, Sewickley, in the county 5 of Allegheny and State of Pennsylvania, have invented a new and useful Improvement in Roof Construction, of which the following is a specification.

The invention relates to roofs which comprise spaced purlins and preformed slabs 10 of cementitious material supported at their ends by purlins, it being understood that the term "purlins" is here used to designate rafters, and other equivalent members, for 15 supporting roof decks.

As customarily constructed, the entire upper faces of slabs for such roofs lie in a common plane, and by reason of this, it has been necessary to provide them with thick bodies 20 of waterproofing material,—three or four layers frequently being required to assure adequate protection against the ingress of water. Because of the amount of material required, and of the labor cost of applying it, 25 the waterproofing of such roofs is quite expensive. Also, the plainness of the surfaces of such a roof gives it an unattractive appearance.

The object of this invention is to provide 30 a roof of the character explained which is so formed as to require a minimum of waterproofing, and less than heretofore required, and which is otherwise economical to construct; a roof which is strong, durable and 35 easy to erect; and a roof which has its surface so interrupted as to give it a pleasing appearance.

In the drawings, Fig. 1 is a plan view of 40 a portion of a roof embodying the invention; Fig. 2 a sectional view taken on the line II—II, Fig. 1; Fig. 3 a sectional view corresponding to Fig. 2 illustrating a modification of construction; Fig. 4 a sectional view taken on the line IV—IV, Fig. 1; Fig. 5 a 45 sectional view corresponding to Fig. 4 illustrating a modification of construction; and Fig. 6 a perspective view of an attaching clip.

In the practice of this invention, the preformed slabs of cementitious material, which 50 may be made of concrete, gypsum and the like, but which are preferably formed of gypsum, have their sides off-set to form gutters between them. The slabs are provided

on their upper or exposed faces with layers 55 of waterproofing material which may be applied in plastic form either before or after the slabs are laid upon a roof, but which are preferably in the form of sheets attached to the slabs before they are laid. These layers 60 of waterproofing material extend downwardly over the gutter-forming sides of the slabs, and monolithic bodies of cementitious material are formed in the gutters to a height 65 sufficient to seal the lower edges of the layers of waterproofing material, but to a less height than the plane of the tops of the slabs. The bodies of cementitious material may be 70 of concrete or gypsum, and may themselves be waterproof, although it is preferred to form the bodies of ordinary concrete or gypsum, and to provide their tops with waterproofing layers. Because the top of each slab is relatively narrow, water will 75 readily flow from it into the gutters formed between the upper portions of the sides of the slabs and above the bodies of cementitious material molded between the sides of the slabs. Accordingly, relatively thin layers 80 of waterproofing material are required for the tops of the slabs. When the monolithic bodies of cementitious material in the gutters are not formed of material which in 85 itself is water resistant, the layers of waterproofing material upon such bodies is heavier or thicker than that upon the tops of the slabs because water may remain in the gutters.

The monolithic bodies of cementitious material formed in the gutters may be provided with reenforcement to cause such bodies to act as beams for strengthening the slabs. However, the slabs may be inherently sufficiently strong to support their own weight and that of the required roof load. 95 For attaching the slabs to purlins, clips are preferably arranged in the lower portions of the gutters between the sides of the slabs and extend downwardly between the slabs, being constructed to engage the flanges of 100 purlins. The upper ends of these clips are anchored in the bodies of cementitious material in the gutters.

Having reference now to the illustrative embodiment of the invention, Fig. 1 shows 105 a plurality of slabs 1 resting at their ends upon the top flanges of purlins 2 which may be channels. The top of each slab is pro-

vided with a layer 3 of waterproofing material which extends downwardly over the sides of the slabs as clearly illustrated. The sides of the slabs may be variously off-set to 5 form gutters 20 between them, the gutters illustrated in Fig. 2 being V-shaped, and those shown in Fig. 3 being reentrant. Each slab may be reenforced longitudinally by 10 welded wire fabric having longitudinal strands 4 arranged substantially in the positions indicated, and having transverse strands 5 the ends of which preferably extend to a face of the slabs in order to support the reinforcing while the slab is being molded. As seen in Fig. 3, the bottoms of the slabs may be hollowed to save material and make them light in weight.

When the slabs have been laid upon the purlins, or while they are being so laid, 20 purlin-attaching clips are arranged between their sides. While various forms of clips may be used, a suitable form is that illustrated in Fig. 6, and which comprises a short horizontal rod 6, the ends of which 25 rest against the tapered or off-set sides of the slabs to hold the upper end of the clip above the bottom of the gutters, and a twisted bar 7 provided at its top with a loop 8 to engage rod 6 and provided at its lower 30 end with laterally extending lip 9 for engaging the flange of a purlin. When the bodies of cementitious material formed in the gutters are reenforced, reenforcing rods 10 may be supported upon the upper ends 35 of the clips to position them for encasement.

After the clips 7 and reenforcing bars 10 are so positioned, bodies 11 of cementitious material are formed in the gutters to a height above the lower edges of waterproofing layers 3, but below the planes of the tops of the slabs, thus forming water-receiving gutters between the slabs. In the embodiment of the invention illustrated in Fig. 2 the lower edges of the waterproofing 45 layers extend but a short distance below the tops of bodies 11, whereas in Fig. 3 these edges extend nearly to the bottoms of the gutters and bodies 21 of asphalt or other waterproofing material are formed in the bottoms of the gutters to further seal the edges of the waterproofing layers, bodies 11 of cementitious material reenforced by rods 10 being formed above the bodies 21 of waterproofing. If desired, the bodies 11 of cementitious material may, as shown in Fig. 55 3, be anchored to the sides of the slabs by nails 22 partially driven into the slabs. The tops of the bodies 11 are, when these bodies are not formed of water-resisting material, provided with a layer 12 of waterproofing material which is of sufficient thickness to resist the penetration of water when lying in the gutters. When the slabs 60 are provided with waterproofing layers 3 in the form of sheets, the ends of the slabs

may, as shown in Fig. 4, be sealed by strips 23 of waterproofing material attached by an asphaltic or other suitable binder.

Not only does the provision of gutters between the slabs make it possible to adequately waterproof the tops of the slabs with layers of waterproofing material thinner than now required for plane-faced roofs, but the gutters break up the continuity of the roof, and thereby give it a pleasing appearance. If desired, the slabs may, as illustrated in Fig. 5, be provided at their ends with gutters 15, similar to those formed between their sides, the tops of the gutters 15 being in the same general plane as the tops 70 of those formed between the sides of the slab. When gutters 15 are formed between the ends of the slabs, the waterproofing layers 3 have their ends sealed in the same general manner as the sides.

According to the provisions of the patent statutes, I have explained the principle and operation of my invention, and have illustrated and described what I now consider to represent its best embodiment. However, I desire to have it understood that, within the scope of the appended claims, the invention may be practiced by other forms of construction than that particularly illustrated and described.

I claim as my invention:

1. A roof comprising spaced purlins, pre-formed slabs of cementitious material supported at their ends by the purlins, the upper portions of the adjacent sides of said slabs being offset to form gutters between the slabs, layers of waterproofing material covering the tops of the slabs and extending downwardly over said gutter-forming sides of the slabs, and monolithic bodies of cementitious material formed in said gutters and sealing the lower edges of said waterproofing layers, the tops of said bodies being below the plane of the tops of the slabs and being waterproof.

2. A roof comprising spaced purlins, pre-formed slabs of cementitious material supported at their ends by the purlins, the upper portions of the adjacent sides of said slabs being offset to form gutters between the slabs, layers of waterproofing material covering the tops of the slabs and extending downwardly over said gutter-forming sides of the slabs, and monolithic bodies of cementitious material formed in said gutters and sealing the lower edges of said waterproofing layers, the tops of said bodies being below the plane of the tops of the slabs and being provided with a heavier layer of waterproofing material than said layers of waterproofing material on said slabs.

3. A roof comprising spaced purlins, pre-formed slabs of cementitious material supported at their ends by the purlins, the upper portions of the adjacent sides of said

slabs being offset to form gutters between the slabs, sheets of waterproofing material attached to said slabs and covering their tops and extending downwardly over their gutter-forming sides, reenforced bodies of cementitious material formed in said gutters and sealing the lower edges of said waterproofing sheets, the tops of said bodies being below the plane of the tops of the slabs and being provided with a layer of waterproofing material.

4. A roof comprising spaced purlins, preformed slabs of cementitious material supported at their ends by the purlins, the upper portions of the adjacent sides of said slabs being offset to form gutters between the slabs, layers of waterproofing material covering the tops of the slabs and extending downwardly of their gutter-forming sides, 15 clips extending from the bottom portion of said gutters between the sides of the slabs and engaging said purlins, monolithic bodies of cementitious material formed in said gutters and encasing the upper ends of 20 said clips to anchor them, said bodies sealing the lower edges of said waterproofing

layers, and the tops of said bodies being below the plane of the tops of the slabs and being waterproof.

5. A roof comprising spaced purlins, preformed slabs of cementitious material supported at their ends by the purlins, the upper portions of the adjacent sides of said slabs being offset to form gutters between the slabs, sheets of waterproofing material 35 attached to the slabs and covering their tops and extending downwardly over their gutter-forming sides, clips extending from the bottom portions of said gutters between the sides of the slabs and engaging said purlins, 40 reinforcing rods resting upon the upper ends of said clips, and monolithic bodies of cementitious material formed in said gutters and encasing the upper ends of said clips to anchor them and also encasing said reenforcing rods, said bodies sealing the lower edges of said waterproofing sheets, and the tops of said bodies being below the plane of the tops of the slabs and being provided with 45 layers of waterproofing material. 50

In testimony whereof, I sign my name.
HERBERT E. MARKS.
